SNAIL BAIT HOLDER

John Torchia, 2140 Telegraph Ave.,
Stockton, Calif. 95204

Filed Mar. 16, 1972, Ser. No. 235,458

Term of patent 14 years

Int. Cl. D22—06

U.S. Cl. D22—19

FIG. 1 is a direct perspective view of a snail bait holder, with a segment broken away and in section.

FIG. 2 is an elevation of the snail bait holder, looking directly at one of the circumferentially spaced access openings.

FIG. 3 is a similar view, but with the snail bait holder rotated approximately forty-five degrees.

FIG. 4 is a bottom plan view of the snail bait holder.

I claim:

The ornamental design for a snail bait holder, as shown.
